LINEAR MODULATOR

John A. Rankin, Port Washington, N. Y., assignor
to Radio Corporation of America, a corporation
of Delaware

Application December 5, 1941, Serial No. 421,711

9 Claims. (Cl. 179—171.5)

This application concerns a new and improved method of and means for generating wave energy and modulating the wave length thereof substantially linearly in accordance with modulating potentials.

More in detail, my disclosure concerns wave length modulators of the type wherein a reactance tube controls the frequency of operation of a generator of wave energy, the reactance tube mutual conductance being in turn controlled by modulating potentials. A feature of my invention is the use of an impedance in the reactance tube cathode circuit wherein a potential is produced which varies in accordance with variations in the current flowing in the reactance tube. The said variations thus are an indication of modulation potential and/or reactance tube distortion and are supplied to an early stage in the modulation potential amplifier in a degenerative sense to correct the said distortion so that the wave length modulation of the oscillations is truly representative of the modulating potentials.

The invention is of wide application in the radio art and may be used in frequency modulators of the Crosby type (Crosby Patent #2,279,659, dated April 14, 1942) wherein the mean frequency of operation of the wave length modulated wave generator is stabilized by deriving from the modulated oscillations a potential which varies in accordance with the variations of the mean frequency thereof, from the correct mean frequency, and applying said derived potentials as a control potential on the reactance tube. By the use of such stabilization in combination with my improved distortion correction method and means, improved results are obtained in that substantially linear wave length modulation of the oscillations generated is obtained.

In describing my invention in detail, reference will be made to the attached drawings wherein:

Fig. 1 illustrates a reactance tube modulated generator wherein a potential is derived in the cathode circuit of the reactance tube and applied degeneratively to an earlier modulation potential stage;

Fig. 2 is a modification of Fig. 1 and includes means for stabilizing the mean frequency of the generated wave; while

Fig. 3 is a modified form of feedback circuit which may be used to replace the feedback circuits of Figs. 1 and 2.

In Fig. 1, 2 is a reactance tube, 10 is a wave generator the frequency of operation of which is to be controlled by the reactance tube 2, 20 is the first stage of a modulation potential am-

plifier, the second stage 30 of which is coupled to an electrode of the reactance tube, and RC is a resistance-condenser combination wherein a potential is produced and supplied by line 40 to the control grid of tube 20.

The oscillation generator may be of any approved type and may, for example, comprise a tube 10 having its anode 11 and grid 12 connected in a regenerative oscillation circuit including tuning condenser C4 and tank inductance L1. The operation of the generator is controlled by the reactance tube 2 which again may be of any approved type such as, for example, of the nature disclosed in Crosby United States application No. 136,578, filed April 13, 1937, now U. S. Patent No. 2,279,659, dated April 14, 1942.

This reactance tube has its anode A connected to a point on circuit L1—C4 and its cathode connected to a second point on said circuit by resistance R and radio frequency bypass condenser C so that the impedance of this tube, that is, the space between its anode and cathode is connected across the frequency determining circuit of the oscillation generator. The anode A is connected by a coupling condenser CC and phase shifting resistance RO and phase shifting condenser CO to ground. A point between RO and CO is connected to the grid G1. The purpose of this phase shifting circuit is to provide a substantial phase quadrature relation between the high frequency voltage on anode A and the current to the anode within the tube, and this circuit comprises RO, the capacity between the grid G1 and cathode K taken with condenser CO and also the capacity of circuit connections, etc.

Thus resistor RO and condenser CO form a phase shifting circuit which shifts the voltage supplied from the tank circuit L1—C4 to the plate A of the reactance tube 2 so that it reaches the grid G1 with a substantially 90 degree phase lag. The value of RO is made high as compared to the reactance of CO for the frequency generated so that current through the circuit RO—CO is larger resistively and is in phase with the voltage. However, the voltage drop through CO lags the current by substantially 90 degrees and the current to the plate A lags the plate voltage by about 90 degrees. Thus the desired phase relation necessary to produce the reactive effect rather than a resistive effect in tube 2 is obtained. This reactive effect is complex but with the particular connections shown is inductive since the current within the tube to the anode A is lagging the voltage on the anode A. Thus the tube 2

provides a reactance which is included in the frequency-determining circuit of the generator.

The size of the reactance provided by the tube 2 is controlled by controlling the conductivity of the tube 2 and this is controlled by modulating potentials from transformer T1 impressed on the grid 21 of tube 20 wherein they are amplified and supplied by coupling condenser CC to the grid 29 of tube 30 and thence by transformer T2 to the grid G1. The amplifiers 20 and 30 are usual and include in the cathode circuits thereof biasing units 23 and 31 and also include other usual features such as bypass condensers BP and the necessary charging resistances, etc.

As stated hereinbefore, the cathode of the reactance tube 2 is returned to ground through a network RC, C being a complete bypass at the frequency of operation of the generator but being small at the modulation frequency so that voltages of modulation frequency and below are developed across R. These voltages are fed back by the lead 40 and resistor 19 to the control grid 21 of the stage 20 of a phase determined by the transformer T2. The phase of the feedback voltages is made such by properly poling the windings of transformer T2 that it opposes the modulation voltage to provide degeneration in the amplifier, reducing the gain thereof and the amount of distortion in the system.

The potential provided by RC and supplied to the initial stage by the lead 40 reduces the distortion inherent in the audio amplifier, made up of tubes 20 and 30, and also reduces the distortion inherent in the reactance tube 2. The circuit further improves the frequency response characteristic of the audio amplifier, thereby giving improved performance to the modulator unit. Note in my system that by taking voltage from the plate cathode circuit of the reactance tube 2, compensation of the non-linearity inherent in the reactance tube is assured.

The modification of Fig. 2 is in many respects similar to the modification of Fig. 1. In the two figures, corresponding elements have been designated by corresponding reference numerals and letters and a detailed description of Fig. 2 is believed unnecessary.

However, in Fig. 2 it will be noted that the phase shifting circuit of the reactance tube 2 now comprises a condenser CO between the anode and grid G1 and a resistance RO between the grid G1 and ground. In this arrangement the resistance RO is small as compared to the reactance of CO and the current through the condenser CO leads the voltage thereacross so that the voltage on the grid G1 leads the voltage on the anode A by about 90 degrees and the current to the anode A leads the voltage thereon, and the desired reactive effect in tube 2 is obtained. Since the current to the anode leads the voltage thereon, the reactive effect is capacitive in nature although it will be understood that these tubes provide complex reactances.

The oscillator 10 in Fig. 1 is of the grounded grid type whereas in Fig. 2 it is of the grounded anode type with the cathode 7 raised above ground potential by radio frequency choke RFC. Moreover, in Fig. 2 the output of the oscillator is shown as comprising power amplifiers and/or amplitude limiters and/or frequency multipliers, as required, all being included in the unit 13.

The generator 10 in Fig. 2 has its mean frequency of operation stabilized in a manner similar to that used by Crosby in his United States application No. 136,578 now U. S. Patent No. 75

2,279,659, dated Apr. 14, 1942. The means to do this comprises a coupled inductance 41, which picks up modulated oscillations from the oscillator A or from a second stage included in 13 and supplies it to a wave deviation detecting means in unit 43. This means may comprise, if desired, wave frequency converting means and a local source of oscillations to mix with the frequency modulated oscillations picked up at 41 and supplied to 43. Alternatively, this means may include a modulated wave amplifier and/or frequency divider.

In any case, the modulated oscillations of a lower frequency or of the frequency picked up at 41 is supplied to a frequency counting circuit of some type such as a frequency discriminator of the two-path type or off-tuned circuit type wherein the frequency variations are converted to amplitude variations and detected in a pair of detectors such as, for example, shown at 50 and 60, so that a differential potential is set up across the resistances 51 and 55, shunted by condensers 53 and 57. The difference of the rectified current is supplied by resistance R1 and C1 to the grid G1 by way of the secondary winding of transformer T2. The time constant circuit R1—C1 is made such that it passes only slow variations in potential characteristic of changes in the mean frequency of the modulated oscillations but does not respective to potentials of modulation frequency.

Comparing circuits 1 and 2, circuit 2 employs in addition to degeneration from the reactance plate cathode circuit to the input of the audio amplifier a second circuit which determines accurately the mean frequency of the main oscillator. Direct current and audio voltage derived from rectifiers 50 and 60 of Fig. 2 are fed to the grid G1 of reactance tube 2 to provide frequency correction and improvement in the linearity of reactance tube 2. At the same time, audio voltage appearing across the impedance RC in the cathode plate circuit of reactance tube 2 is fed to the input of the audio amplifier tubes 20 and 30 to further increase the linearity of reactance tube 2, reduce the distortion inherent in the audio amplifier, and correct the frequency response of the audio amplifier. These two operations are separate and independent so that improvement derived so far as linearity is concerned from the application of voltage rectified by tubes 50 and 60 will enhance the improvement derived by the degenerative connection between the plate cathode circuit of reactance tube 2 and the input of the audio amplifier comprising tubes 20 and 30.

The arrangements of Figs. 1 and 2 may be modified as shown in Fig. 3, wherein the potential drop across RC is supplied by way of line 40 to the cathode 25 of tube 20 in place of the grid G1. Degeneration may be accomplished in this manner because RC is a low impedance source and can be coupled back directly to the cathode of the tube 21.

What is claimed is:

1. In a signaling system, a tube reactance the reactive value of which is controllable, a source of control potentials, a tube amplifier, having a control electrode, coupling said source of control potentials to said reactance tube, an impedance in the path between two electrodes of said reactance tube, and a circuit degeneratively coupling said impedance to the control electrode in said tube amplifier.
2. In a signaling system, a controllable tube reactance which is included in a signaling circuit

for determining the reactance of the signaling circuit, a source of control potentials, a multiple stage tube amplifier coupling said source of control potentials to said reactance tube, an impedance in the path between two electrodes of said reactance tube, and a circuit degeneratively coupling said impedance to an early stage of said amplifier.

3. In a signaling system, a tube reactance the reactive value of which is controllable, said tube having output electrodes between which said reactive effect appears and having a control electrode, a source of control potentials, an amplifier tube having an input coupled to said source of control potentials and an output coupled to the control electrode of said reactance tube, and a circuit degeneratively coupling the output electrodes of said reactance tube to the input of said amplifier.

4. In a signaling system, a controllable tube reactance which is included in a signaling circuit for determining the reactance of the signaling circuit, a source of control potentials, an amplifier including a plurality of multiple electrode tubes coupled in cascade and coupling said source of control potentials to said reactance tube, an impedance in a path between two electrodes of said reactance tube, and a circuit degeneratively coupling said impedance to an electrode of a tube in an early stage of said amplifier.

5. In a signalling system, a tube reactance the reactive value of which is controllable, a source of control potentials, a tube amplifier having a control electrode, connections including said tube amplifier coupling said source of control potentials to said reactance tube, an impedance in the path between two electrodes of said reactance tube, and a circuit degeneratively coupling said impedance to the control electrode in said tube amplifier.

6. In a signalling system, a controllable tube reactance which is included in the frequency determining circuit of an oscillation generator, said reactance tube having a plurality of electrodes, a source of control potentials, a tube amplifier, having a control electrode, coupling said source of control potentials to said reactance tube, an impedance in a path between two electrodes of said reactance tube, a circuit degeneratively coupling said impedance to the control electrode in

5 said tube amplifier, and connections for controlling the frequency of operation of said generator in accordance with deviations in the mean frequency of operation thereof.

7. In a signalling system, a source of control potential, a tube reactance the reactive value of which is controllable, said reactance tube having electrodes including a cathode and an output electrode, an impedance in a circuit connected between said cathode and output electrode, a tube amplifier, having a control grid and a cathode, coupling said source of control potentials to said reactance tube, a connection between the cathode of said tube amplifier and the end of said impedance remote from the cathode of said tube reactance and a circuit connecting the end of said impedance connected to the cathode of said reactance tube to the control grid of said tube amplifier.

8. In a signalling system, a tube reactance the reactive value of which is controllable, said tube reactance having an output electrode and cathode, a source of control potentials, a tube amplifier having a control grid and a cathode, connections coupling said source of control potentials to said tube amplifier, connections coupling the said tube amplifier to said reactance tube, an impedance in a connection between the output electrode and cathode of said reactance tube, a connection between the reactance tube cathode end of said impedance and the cathode of said amplifier tube and a connection between the control grid of said amplifier tube and the end of said impedance remote from the cathode of said reactance tube.

9. In a signalling system in combination a tube reactance the reactive value of which is controllable, said tube having electrodes including a cathode, a source of control potentials, a tube amplifier coupling said source of control potentials to said reactance tube, said tube amplifier having a control electrode and cathode, a resistance in the cathode return circuit of said reactance tube, and connections between said resistance and the control grid and cathode of said tube amplifier for utilizing the voltage developed across said resistance to control the gain of said amplifier in a degenerative sense.
